UNITED STATES PATENT OFFICE.

WILLIAM C. WEAVER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 29, 1923. Serial No. 671,361.

To all whom it may concern:

Be it known that I, WILLIAM C. WEAVER, a citizen of the United States, residing at East Orange, in the county of Essex and State of New Jersey, have invented certain new and useful Improvements in Telephone-Exchange Systems, of which the following is a full, clear, concise, and exact description.

10 This invention relates to telephone exchange systems and more particularly to systems involving the use of machine switching apparatus for the establishment of connections.

15 In exchange systems of the above mentioned character it is desirable to enable connections to be established from distant toll points to any subscriber's line in the exchange area over the automatic switching mechanism of the exchange. Two methods of establishing such connections may be employed, depending upon the nature of the equipment at the toll point. If the toll point is equipped entirely with manual apparatus, a connection may first be obtained over a toll line with the toll switching operator who may then, by means of key indicator equipment, select an idle trunk extending to the office of the exchange in which the wanted line terminates and under the control of the key indicator sender complete the connection over the selected trunk by means of selector switches. If the toll point is another exchange area of the machine switching character, the connection with the wanted line may be established entirely by automatic selector switches under the control of such distant toll operator.

20 In either case it is desirable to enable the toll operator who is responsible for the establishment of the connection to be able to initiate the application of ringing current to the wanted line and in the event of a connection to a private branch exchange line to re-ring the operator at such branch exchange when occasion arises.

25 It is, therefore, an object of the invention to enable toll calls originating at distant toll points to be completed to the lines of subscribers in a machine switching area by means of selector switches and to permit the toll operator to control the application of ringing current to the wanted line.

30 More particularly, it is an object of the

invention to provide means at an incoming toll selector under the control of a distant toll operator for initiating the automatic application of ringing current to a wanted line, the ringing current being cut-off upon the response of the called subscriber, and, if the wanted line is a private branch exchange line, for reringing the private branch operator, the ringing current being applied and cut-off at the will of the toll operator.

35 A feature of the invention is the provision, in a selector circuit, of a ringing relay which, when initially operated under the control of ringing current applied to the incoming end of the circuit, is locked in an operated condition and applies ringing current to the outgoing end of the circuit until the called subscriber or private branch exchange operator responds. If the call is terminated on a private branch exchange line, circuit changes are effected whereby the ringing relay is rendered responsive to each application of ringing current to the incoming end of the circuit for the purpose of re-ring the private branch exchange operator.

40 This and other features contemplated in the present invention will become more clearly understood from a consideration of the accompanying drawings and the appended claims.

45 Referring to the drawings, Fig. 1 shows at the right a trunk circuit outgoing to a full mechanical office of an exchange area and accessible from a toll point shown in the upper left portion of the figure, or, from a toll point of a different character as shown in the lower left portion of the figure. In the lower right corner of the figure, a key indicator link is diagrammatically illustrated. This link is under the control of the toll operator whose position is shown in the upper left portion of the figure.

50 Fig. 2 shows an incoming selector circuit in which the trunk circuit of Fig. 1 terminates, together with the control circuits thereof, and ringing control apparatus embodying the present invention.

55 Fig. 3 shows a final selector switch accessible from the incoming selector switch of Fig. 2 together with the control circuits thereof, a multi-station subscriber's line terminating therein, and a private branch exchange line terminating at an operator's po-

sition. The brushes of a second final selector having access to certain stations terminals of the party line are also illustrated.

Two types of toll points are disclosed in Fig. 1, the one shown in the upper left portion of the figure comprising a toll operator's position O provided with a toll cord and associated key indicator mechanism. While this toll cord has been shown as having access directly to a calling line for answering calls initiated thereby, it would, in practice, be associated with the usual recording operator's position and calls would be handled thereto in accordance with the standard toll practice. In order to simplify the disclosure, however, only the toll switching operator's position O has been disclosed and it will be assumed herein that the toll operator makes direct connection with the calling line. The toll point at which the operator's position O is located is provided with key indicator mechanism diagrammatically disclosed in the broken line rectangle in the lower right corner of Fig. 1. This key indicator mechanism may be of the general type disclosed in the patent to L. M. Allen, No. 1,513,362 issued Oct. 28, 1924. This key indicator mechanism comprises a plurality of office senders, a keyboard for each toll operator's position and a plurality of links for associating keyboards, senders and outgoing trunks with each other. Each link circuit is provided with a plurality of trunk selecting switches for selecting an idle trunk from the groups extending to the several offices of the exchange, a sender selector for associating an idle sender with the selected outgoing trunk and an operator's position finder for associating the selected sender with the keyboard of the toll operator's position.

The toll line 174 and toll district selector 175 shown in the lower left portion of Fig. 1 are employed for establishing toll connections from a distant toll point of a mechanical switching area and may be of the general type disclosed in the application of W. C. Jordan, Serial No. 680,807, filed Dec. 15, 1923.

The selector switches shown in Figs. 2 and 3 are of the well known revertive impulse power driven type and may be in general the same as the switch described in the patent to E. B. Craft and J. N. Reynolds, No. 1,123,696, issued January 5, 1915.

It is thought that the invention will be best understood from a detailed description of the manner in which toll connections may be established. It will first be assumed that the calling subscriber A desires to establish a toll connection with the party line shown in Fig. 3 and with the substation B thereof, this connection being established through the toll operator's position O. Assume that the toll operator has received the informa-

tion regarding the desired toll call, this information including the number of the calling subscriber's line, the name of the office containing such line, the name of the office containing the wanted subscriber's line and the number of such line. Having learned the name of the office and the number of the wanted subscriber's line therein, the toll operator depresses a key (not shown) associated with the key indicator mechanism and individual to such office and initiates the operation of one of the switching units, such, for example, as disclosed in the broken rectangle of Fig. 1. The switching unit thereupon functions to select an idle sender, the stepping relay 128 only of which is disclosed; to select the position of the operator who is initiating a call; and to select an idle trunk from the group of trunks extending to the office in which the desired line is located.

After trunk selector 150 has selected an idle trunk from the group, it being assumed that the trunk 118, 119 is idle and is selected, a visual indication of the identity of the selected trunk is displayed before the operator in the usual manner in order that she may know which one of the total number of trunks she is to employ in making the connection. Observing the indication of the trunk selected, the operator inserts the plug 116 of a holding cord circuit 115 in the jack 117 of such trunk. Holding cord 115 is for the purpose of maintaining the set condition of switches which later establish the connection from the trunk 118, 119 to the wanted subscriber's line in order that such line may not be seized by other switches and made busy while the toll operator is completing the connection. The insertion of the plug 116 in the jack of the selected trunk completes a circuit from battery over the sleeve of said plug and jack, conductor 120 and winding of relay 108 to ground. Relay 108 operates connecting ground potential at its inner left armature to conductor 114 and the multiples of terminal 127 in other trunk selector switches similar to the switch 150 to render such trunk non-selectable. In addition, ground potential is applied to the multiples of terminal 111 appearing in all the district selector switches similar to 175 to prevent the trunk from being seized by toll district selectors under the control of toll lines, such as 174. After the register sender has taken its complete setting in accordance with the designation of the wanted subscriber's line, the fundamental circuit is completed for controlling the brush selecting operation of the incoming selector switch shown in Fig. 2. This circuit may be traced in part from battery, through the left winding of relay 205, the upper contacts of cam 209, the lower right contact of cam 215, the upper

left contact of cam 206, conductor 235, conductor 230, brush 125 thence through the stepping relay 128 and associated circuits of the key indicator sender, brush 126, conductors 231 and 236 to ground through the lower contacts of cam 207. Relays 128 and 205 energize in the fundamental circuit. Relay 205 completes a circuit from ground at its right armature and front contact 10 through the lower left contact of cam 212 to battery through the magnet winding of sequence switch 210 for advancing the sequence switch out of position 1 and into position 2 where a circuit is closed for the up-drive power magnet 218. This circuit may be traced from battery through the winding of magnet 218, the lower right contact of cam 212 to ground at the right front contact of relay 205. In position 2 of the sequence switch, relay 205 is maintained energized in a circuit from battery through its left front contact and the lower right contact of cam 215 thence over the fundamental circuit to ground as described. 15

25 The up-drive magnet 218 causes the brushes of the selector to move upwardly and for each brush tripping position passed over, a circuit is closed as follows for shunting out the stepping relay 128, maintaining the relay 205 operated: battery, through the left winding and left front contact of relay 205, lower contacts of cam 215, commutator 230, brush 228 to ground at the lower left contact of cam 213. The stepping relay 128 is deenergized each time the above traced shunt circuit is closed and the register sender operates to determine the amount of movement imparted to the switch. When the proper set of brushes is reached, the 20 sender opens the fundamental circuit in the usual manner and as soon thereafter as the brush 228 engages an insulated segment on commutator 230, the relay 205 retracts its armatures and opens the circuit of the up-drive power magnet 218. Relay 205 also closes a circuit from ground, through its right back contact, lower left contact of cam 211 to battery through the winding of sequence switch 210 driving said sequence switch out of position 2 and into position 3. 25

In position 3 of sequence switch 210, the fundamental circuit is again closed in the manner above described and relay 205 again energizing closes the previously traced circuit over its right front contact for advancing sequence switch 210 into position 4. In position 4, relay 205 remains energized and completes the circuit for the up-drive power magnet 218 for driving the switch shaft upwardly in its group selecting movement. The tripping magnet 219 energizes in position 3 of sequence switch 210 over a circuit closed at the lower contacts of cam 214 and positions the tripping spindle of the switch 30 so that during the initial portion of the

group selecting movement of the switch shaft the selected set of brushes is tripped to encounter the multiple terminals of the bank. For each group of terminals traversed by the tripped set of brushes, a circuit is closed from battery, through the left winding and left front contact of relay 205, the lower right contact of cam 215, the upper right contact of cam 206, commutator 231, brush 227 to ground at the lower left contact of cam 213. 35

The closure of this circuit holds the relay 205 energized and shunts out the stepping relay 128. When the register of the sender has become satisfied, the fundamental circuit is opened and relay 205 becomes de-energized, immediately that the brush 227 encounters the next insulating segment of commutator 231. Relay 205 opens the circuit of the power magnet 218 and completes a circuit from ground, through its right back contact and the lower left contact of cam 211 for advancing sequence switch 210 into position 5. 40

In position 5 of sequence switch 210, a circuit is closed from battery through the right winding of relay 205 to ground through the right contacts of cam 234. Relay 205 operates and locks in the following circuit provided the first trunk in the group upon the terminals of which the brushes 221, 222 and 223 are now standing is busy: battery, through the left winding and left front contact of relay 205, upper contacts of cam 214, brush 223 to the grounded test terminal of the busy trunk. Relay 205 at its right front contact closes a circuit over the lower left contact of cam 212 for driving sequence switch 210 into position 6. Relay 205 remains energized in this position and completes a circuit from its right front contact, the lower right contact of cam 212 to battery through the winding of up-drive power magnet 218 whereby the brush shaft is driven upwardly to move the brushes 221, 222 and 223 over the terminals of the group to hunt for an idle trunk line. When the first idle trunk is reached, no ground potential being present upon the test terminal, the holding circuit of relay 205 is opened. This relay, however, remains energized for an instant by means of a circuit from battery, through the right winding of said relay, lower right and upper left contacts of cam 234, commutator 232, brush 229, the upper contact of cam 213 to ground at the right front contact of relay 205. When the brush 229 engages the next insulating segment of commutator 232, relay 205 is deenergized and the circuit of the magnet 218 is opened, causing the brush shaft to cease its upward movement. Relay 205, at its right back contact closes a circuit extending over the lower left contact of cam 211 for advancing 45

sequence switch 210 out of position 6 into position 7.

In position 7 of sequence switch 210, a circuit is closed from battery, through the left winding of relay 205, upper contacts of cam 209, lower contact of cam 216, brush 222, trunk conductor 225, upper left and lower right contacts of cam 305 to ground at the lower left contact of cam 306. Relay

10 205 becomes energized and closes a circuit through its right front contact for driving sequence switch 210 out of position 7 into position 8. While sequence switch 210 is moving from position 7 to position 8, relay 205 is held energized over its left winding and left front contact, lower contact of cam 216 to ground as traced.

The trunk 224, 225 selected by the incoming switch is held busy so as not to be 20 selectable by other switches by means of ground potential placed on the test conductor 226. This potential is applied from ground, through the right contacts of cam 214, test brush 223 and thence to the 25 multiple terminals of the test conductor 226 before all other switches.

The fundamental circuit for controlling the brush tripping movement of the final selector switch, shown in Fig. 3, is now completed and may be traced from battery, 30 through the right winding of relay 300, the lower left contact of cam 303, the lower left contact of cam 302, conductor 224, brush 221, the right contact of cam 217, trunk conductor 225 thence as traced through the sender, returning over conductor 226, the upper contact of cam 212 to ground at the right front contact of relay 205. Relay 300 energizes and closes a circuit for relay 321 which may be traced from battery, through the left winding of this relay, upper left contact of cam 307, left front contact of relay 300 to ground at the upper contact of cam 308. Relay 321 energizes in this circuit

40 and at its left front contact closes a locking circuit for itself extending from battery, through its left winding, back contact of relay 324, left front contact of relay 321 to ground on conductor 226. Relay 321, upon 45 energizing, closes a circuit extending from ground, at its right front contact over the lower contacts of cam 309 to battery through the magnet winding of sequence switch 310 for advancing sequence switch 310 into position 2. When sequence switch 310 moves out of position 1, the initial energizing circuit of relay 300 is opened at the lower contact of cam 303, the relay 300 remaining energized over the fundamental 50 circuit by reason of a locking circuit extending from battery, through its right winding, lower contact of cam 340, the right front contact of relay 300, the lower right contact of cam 303 thence to ground over 55 the fundamental circuit as previously

traced. Relay 300, upon energizing, and with sequence switch 310 in position 2, closes a circuit for the high speed up-drive magnet 326 extending from battery, through the winding of magnet 326, the upper right contact of cam 311, the left front contact of relay 300 to ground at the upper contact of cam 308. Magnet 326, upon energizing, advances the switch shaft of the final selector 70 in its brush selection movement. As the switch shaft approaches each brush selection position, the brush 336 engages a conducting portion of commutator 330, thereby establishing a shunt around the winding of the stepping relay of the sender, maintaining relay 300 energized. This shunt circuit may be traced from battery, through the right winding of relay 300, the lower contact of cam 340, the right front contact of relay 300, the lower right contact of cam 303, the upper right contact of cam 302, commutator 330, brush 336, the right contact of cam 307, the left front contact of relay 300 to ground at the upper contact of cam 308. As soon as the sender register is satisfied, the fundamental circuit is opened at the sender and as soon thereafter as brush 336 engages the next insulating portion of commutator 330, the holding circuit of relay 300 is opened and relay 300 deenergizes. 85 As soon as relay 300 retracts its armatures, the circuit of the up-drive magnet 326 is opened and a circuit is established from ground at the upper contact of cam 308, the left back contact of relay 300, the lower right contact of cam 312 to battery through the magnet winding of sequence switch 310, for advancing the sequence switch 310 into 90 position 3. With the sequence switch in position 3 a circuit is closed from ground at the lower right contact of cam 306 through the winding of tripping magnet 335 for rotating the tripping spindle preparatory to 95 tripping the selected set of brushes.

When sequence switch 310 reaches position 100 3, the energizing circuit of relay 300 and the stepping relay 128 of the sender is again established. Relay 300 again establishes the previously traced circuit for advancing sequence switch 310 out of position 105 3 into position 4. In position 4, the circuit of the up-drive magnet 326 is again established as previously traced for advancing the switch shaft in its group or tens selection movement. During the initial portion 110 of this movement, the selected set of brushes is tripped in the well known manner. As the switch shaft approaches its first group selection position, the brush 338 engages the lowermost conducting portion of commutator 337 and a circuit is closed in shunt of the stepping relay of the sender and may be traced from battery, through the right winding of relay 300, the lower contact of cam 340, the right front contact of relay 115 120 125 130

300, the right contacts of cam 303, commutator 337, brush 338 and thence as traced to ground at the upper contact of cam 308. As the switch shaft advances, the sender 5 stepping relay is intermittently shunted until the sender register is satisfied when the fundamental circuit is opened at the sender. As soon thereafter as the brush 338 engages the next insulating portion of the 10 commutator 337, relay 300 deenergizes, opening the circuit of the up-drive magnet 326 and closing the previously traced circuit over the lower right contact of cam 312 for advancing sequence switch 310 into 15 position 5.

In position 5, the fundamental circuit is again established and relay 300 energizes, advancing sequence switch 310 into position 6. With relay 300 energized and sequence 20 switch 310 in position 6, a circuit is established for the low speed up-drive power magnet 339 extending from battery, through the winding of this magnet, the lower left contact of cam 307, the left front contact of relay 300 to ground at the upper contact of cam 308. Magnet 339, upon energizing, advances the switch shaft in its units selection movement. During this upward movement of the switch shaft an intermittent shunt 25 circuit is established which may be traced from battery, through the left winding of relay 300, the lower contact of cam 340, the right front contact of relay 300, the lower right contact of cam 303, the upper right contact of cam 302, commutator 330, brush 336, thence as traced to ground at the upper contact of cam 308. Relay 300 is maintained 30 energized in this shunt circuit but the sender stepping relay is intermittently deenergized until the sender register is satisfied when the fundamental circuit is opened at the sender. As soon thereafter as the brush 338 engages the next insulating portion of commutator 330, relay 300 retracts its armatures, opening the circuit of the up-drive magnet 339 and closing the previously traced circuit for driving the sequence switch 310 out of position 6 and into position 9.

The brushes 352, 353 and 342 have now 35 been positioned upon the terminals of the desired line and the final selector switch thereupon proceeds in the usual manner to test the line for its busy or idle condition. Assuming that the wanted line is found to be idle, the sequence switch 310 is advanced through intermediate positions from position 9 into the talking position 15, in which position the talking circuit from conductors 224 and 225 is established over the lower contacts of cam 302 and the upper contacts of cam 305, brushes 352 and 353 to the conductors of the called line.

When sequence switch 310 leaves position 40 8½ the circuit hereinbefore traced for relay 205 is opened at the lower left contact of cam 306 and relay 205 thereupon deenergizes. Relay 205, upon deenergizing, closes a circuit from ground at its right back contact over the lower left contact of cam 211 for advancing sequence switch 210 out of position 8 and into position 9. With sequence switch 210 in position 9, relay 205 is connected in a circuit extending to the key indicator sender which may be traced from battery, through the left winding of relay 205, the right contacts of cam 209, conductors 236 and 231 and thence through the sender, returning over conductors 230 and 235, the upper left contact of cam 206 to ground at the upper left contact of cam 215. Relay 205 energizes in this circuit and at its right front contact closes a circuit for advancing sequence switch 210 from position 9 into position 11. As the sequence switch is passing from position 9 into position 11, relay 237 is energized over the lower contact of cam 241 for the purpose of opening the ringing control circuit and to disconnect ground from the tip conductor 235 of the trunk circuit.

When the register sender has completed its function of controlling the selection movement of the switches, ground potential is applied to conductor 124 in the manner described in the patent to L. M. Allen hereinbefore referred to. The application of this ground results in the closure of a circuit from battery, through the right winding of relay 109, right front contact of relay 108, conductor 124, brush 123 and thence to ground. Relay 109 operates and locks in a circuit extending from ground, through its left winding and left front contact, resistance elements 105 and 106 to battery. At its right contact, relay 109 establishes an obvious circuit for relay 110 which completes the connection from conductors 118 and 119 to trunk conductors 235 and 236 respectively. At its lowermost front contact, relay 110 applies ground potential to conductor 114 and to the multiples of terminal 127 for rendering the trunk non-selectable. In addition, relay 110 at its lower front contact connects ground to conductor 238 whereupon a circuit is established over the contact of cam 208, the lower left and upper right contacts of cam 209 to battery through the left winding of relay 205. Relay 205 thereupon energizes closing a circuit over its right front contact and the lower left contact of cam 212 and to battery through sequence switch magnet 210 for advancing the sequence switch from position 11 into position 13. As soon as the sequence switch leaves position 11, relay 237 deenergizes. After sequence switch 210 leaves position 11, relay 205 is maintained locked to ground on conductor 238, over its left winding and left front contact and the left contacts of cam 209. The switches remain in

45 50 55 60 65 70 75 80 85 90 95 100 105 110 115 120 125 130 135

this condition until the toll operator initiates the ringing functions.

- The toll operator, by means of the plug 104, establishes connection with the jack 103 and thence in the well known manner with the calling line A and to complete the toll connection to the called subscriber's line withdraws the plug 116 from the jack 117 and inserts the plug 112 in place thereof.
- 10 As soon as the plug 116 is withdrawn from the jack 117, relay 108 deenergizes and closes a circuit for relay 107 extending from battery, through the winding of this relay, uppermost front contact of relay 110, outer 15 left back contact of relay 108, the inner normal contacts of relay 107 to ground at the common timing device as indicated. Relay 107 thereupon energizes, locking itself directly to ground at the front contact of its 20 inner armature. At its outermost armature contact, relay 107 closes a starting circuit for the timing device which, after a time interval in the manner fully set forth in the patent to F. J. Scudder, No. 1,517,257, is- 25 sued Dec. 2, 1924, establishes a circuit for releasing relay 109 if the operator fails to insert the plug 112 in the jack 117 within a predetermined period. Assuming that the operator changes plugs quickly, relay 108 30 again energizes over conductor 120 and the sleeves of jack 117 and plug 112 to battery through the winding of relay 113 before the timing circuit has completed its function and consequently relay 107 is released at the 35 outer left back contact of relay 108 before the timing circuit functions to shunt down relay 109.
- With the plug 112 in the jack 107, the operator's cord circuit is connected with the 40 trunk 235,236 and the completed connection is in condition for the ringing operation. Relay 113 bridges supervisory relay 100 across the strands of the cord circuit where- 45 upon relay 100 operates to light lamp 101 as a ringing signal. The circuit of relay 100 extends from battery right winding of coil 200 outer right back contact of relay 201, lower left winding of repeating coil 239, upper contacts of cam 207, conductors 236, 119, 50 ring contacts of jack 117 and plug 112, front contact of relay 113, winding of relay 100, tip contacts of plug 112 and jack 117, conductors 118 and 235, lower contacts of cam 206, upper left winding of repeating coil 239, inner contact of relay 201, left winding of coil 200, to ground at the outer back contact of relay 237. To initiate ringing, the toll operator depresses the ringing key 121 thereby bridging the ringing source 122 55 across the tip and ring strands of the cord circuit. Current thereupon flows from source 122 over the lower alternate contact of key 121, ring contacts of plug 112 and jack 117, conductor 119, conductor 236, the 60 upper contacts of cam 207, the lower left

winding of repeating coil 239, condenser 240, relay 202, the upper left winding of repeating coil 239, lower contacts of cam 206, conductors 235 and 118, tip contacts of jack 117 and plug 112 to ground at the upper alternate contact of key 121. Relay 202 responds to the ringing current and establishes a circuit for relay 242 which may be traced from ground, inner back contact of relay 237, contact of relay 202, back contact 70 of relay 262, inner left normal contacts of relay 242 to battery at the innermost lower back contact of relay 204. Relay 202 also closes a parallel circuit through the right winding of relay 201 which upon attracting 75 its armatures, removes the windings of coil 200 from across the incoming end of the trunk circuit 235, 236 thereby extinguishing the lamp 101.

Relay 242 energizes in the circuit previously traced, locking itself directly to ground at its inner left front contact, short-circuits the lower right winding of repeating coil 239 through its outer left front contact and at its right front contact establishes a circuit for pick-up relay 244. This circuit may be traced from battery through the winding and inner left normal contacts of relay 244, right front contact of relay 242 to ground through the right contacts of cam 243. Relay 244 upon energizing locks over its inner left front contact, the back contact of relay 245, to ground at the inner back contact of relay 237 and also establishes a circuit from ground at its outer left contact to battery through the winding of ringing relay 204. Relay 204 upon energizing in this circuit closes a circuit for alternately applying ringing current from the source 249 and battery to the called line. This circuit may be traced from the ringing source 249, through the interrupter 248 or battery through the interrupter 247, through the right contact of cam 246, ringing cut-off relay 245, inner right front contact of relay 244, lower front contact of relay 204, upper contact of cam 216, brush 222, conductor 225, upper contacts of cam 305, brush 353, ring side of the called line to ground through the bell 314 of station B and to ground through the bell 313 of the other substation whose bell is connected to the same side of the line. Through the operation of interrupters 247 and 248, the bells 313 and 314 are operated in accordance with a "one-ring" code. During the application of ringing current, ringing relay 204 connects ground over its innermost upper front contact, the upper left contact of cam 217, brush 221, conductor 224, lower contacts of cam 302, brush 352 and thence to the tip side of the called line for shunting out the bells 316 and 317 of the other two substations to prevent their operation.

Assuming that the subscriber at substation 130

B, recognizing the ringing of his bell as a call for his particular substation, removes his receiver from the switch hook a circuit is established for cutting off the ringing current as soon as the interrupter 247 reaches a position in which direct battery current is connected in the ringing circuit. In response to the removal of the called party's receiver, relay 245 responds, opening at its 10 armature and back contact the locking circuit of relay 244. Relay 244 thereupon de-energizes, opening the circuit of relay 204 which disconnects the source of ringing current and connects the called line through to the right windings of the repeating coil 239. As soon as the operator releases the ringing key following the initiation of ringing, relay 202 releases, releasing relay 201, which again establishes the circuit of relay 100 to light 20 lamp 101.

As soon as the called line is connected through to the repeating coil 239, a circuit is established for supervisory relay 203, extending from battery, through the lower 25 winding of relay 203, the lower right winding of repeating coil 239, the lowermost back contact of relay 204, thence as previously traced to the ring side of the called line, through the substation B returning over the 30 tip side of the line to the left contact of cam 217, thence through the innermost upper back contact of relay 204, the upper right winding of repeating coil 239 to ground through the upper winding of relay 35 203. Relay 203 energizes, closing an obvious circuit through the left winding of relay 201 which again disconnects the windings of battery feed coil 200 from the left windings of repeating coil 239. Relay 262 operates at this time but is without function. With coil 200 disconnected, no circuit is effective over the trunk to the toll operator's 40 position for maintaining relay 100 energized. Relay 100 thereupon deenergizes and extinguishes the lamp 101, this lamp having been lighted through the operation of relay 100 from the time the toll operator released the ringing key following the initiation of ringing, up to the time the called party responded. With the lamp 101 extinguished the toll operator is apprised of the fact that the called party has answered and that talking may then take place over the established 45 connection shown in heavy lines between the subscribers' stations. The operator may listen in on the connection when necessary by connecting her headset 129 to the cord circuit by depressing key 102.

Had a connection been desired with a 60 party on the called line whose bell is shown at 313, then the incoming selector would have been set to select a final selector in a different group having access to the same party line and consequently the brush 228 would 65 have been in engagement with commutator

250. Therefore, when sequence switch 210 reached position 13, relay 237 becomes energized over a circuit from battery through the winding of relay 237, the upper left contact of cam 241, commutator 250, brush 251, thence to ground at the lower left contact 70 of cam 213. With relay 237 energized, a circuit is established from ground at its inner right front contact, lower right contact of cam 211 to battery through the winding 75 of sequence switch magnet 210 for advancing sequence switch magnet 210 from position 13 into position 15. As soon as sequence switch 210 reaches position 13½, relay 237 becomes deenergized. A ringing signal is 80 transmitted to the toll operator through the operation of supervisory relay 100 over the circuit previously traced. Supervisory relay 100, upon energizing in this circuit, lights the lamp 101 to apprise the 85 operator that she may proceed to ring. When the operator operates ringing key 121, relay 202 operates as previously described, closing the circuit of relay 201 for extinguishing the lamp 101, and closing the previously traced circuit for relay 242. Relay 242 energizes and in turn causes the operation of relays 244 and 204. In this case however, relay 244 energizes over the upper 90 contacts of cam 244 to ground through interrupter 256. Ringing current and battery are now applied to the called line over the circuit previously traced but through the interrupters 253 and 252 and the left contact of cam 246. The bells 313 and 314 are now 95 operated in accordance with a "two-ring" code. The response of the called party results, as before described, in the cutting off of the ringing current, the operation of relay 203, and the extinguishing of the lamp 101 to indicate the response of the called party.

The ringing of the other two parties of the party line, the bells 316 and 317 of which are shown, is accomplished in the above described manner but with different settings of the final selector brushes.

When the conversation is terminated and the called party restores his receiver to the switchhook, relay 203 deenergizes opening 115 the circuit of relay 201 which connects the windings of coil 200 in series with the left windings of repeating coil 239. The circuit of supervisory relay 100 at the toll board is now established, as before described, and the lamp 101 is lighted to signal the toll operator that the connection is no longer required. In response to this signal, the toll operator withdraws the plug 112 from the jack 117, releasing relay 108. Relay 108, upon releasing, closes the previously traced circuit of relay 107, which, through the timing circuit, connects ground potential over the intermediate front contact of relay 107 to the junction of resistance ele- 120 125 130

ments 105 and 106. Ground potential being now connected to both terminals of the left winding of relay 109, relay 109 deenergizes opening the circuit of relay 110 which in turn removes busy ground potential from the multiples of terminals 127 and 111 and opens the holding circuit of relay 205. Relay 205 deenergizes and at its right back contact closes a circuit for relay 237 extending from battery, through the winding of relay 237, the right contact of cam 241 to ground at the right back contact of relay 205. Relay 237, upon energizing, closes a circuit from ground at its inner right front contact over the lower right contact of cam 211 for advancing sequence switch 210 from either position 13 or position 15 in which it is standing during the time the subscribers were conversing, into position 18. 10 As soon as the sequence switch 210 leaves position 16, the circuit of relay 237 is opened and relay 237 deenergizes. When sequence switch 210 reaches position 18, a circuit is established for the down-drive magnet 220 15 extending from battery, through the winding of this magnet to ground over the lower contacts of cam 213. Magnet 220 drives the switch shaft downwardly into its normal position where a circuit is established for 20 advancing sequence switch 210 into its normal position. This circuit may be traced from battery, through the winding of magnet 210, the upper right contact of cam 211, segment 233, brush 227 to ground at 25 the lower left contact of cam 213. All apparatus of the incoming selector is now in normal position. When the sequence switch 210 moved out of position 16, ground potential was removed at cam 214 from the 30 brush 223, releasing relay 321. The release of the final selector then proceeds in the well known manner.

The toll operator having released the mechanical equipment through the removal 45 of the plug 112 from jack 117 may entirely release her position apparatus by removing the plug 104 from jack 103. All apparatus employed in the establishment of the connection is now in normal condition and may 50 be employed in the establishment of other connections.

Had the toll connection been established over the incoming selector and final selector with a private branch exchange line 322 55 and 323, the initial ringing up of the private branch exchange operator would have been accomplished in the manner previously described, the private branch exchange operator receiving a signal in response to the 60 ringing current through the operation of ring-down relay 325. On such calls, however, the toll operator is enabled to re-ring the private branch exchange operator if it becomes necessary to call the operator in upon 65 the established connection after she has once

responded and her cord circuit is still connected to line 322, 323. Following the initial application of ringing current and the response of the operator, relay 203 is energized over the windings of bridging coil 327 of 70 the branch exchange operator's cord circuit and remains energized so long as the cord plug is in jack 331, and therefore relay 262 is energized over an obvious circuit extending through the contacts of cam 254 75 and the front contact of relay 203. When, therefore, the toll operator again throws the ringing key 121 for re-ringing the private branch exchange operator and relay 202 operates, a circuit is established from 80 ground, through the inner right back contact of relay 237, the front contact of relay 202, the armature and front contact of relay 262 to battery through the winding of ringing relay 204. Relay 204, therefore, energizes upon each depression of the ringing key 121 and applies ringing current from the source 255 through the inner right back contact of relay 244, the lower front contact of relay 204, thence out over 85 the circuit previously traced, conductor 323, ring contacts of jack 331 and plug 332, through the ring-down relay 328 of the private branch exchange operator's cord circuit, thence returning over the tip contacts 90 of the plug and jack to conductor 322 thence as previously traced to ground at the innermost upper front contact of relay 204. Relay 262 is held operated during the operation of ringing relay 204 over a circuit extending from battery, through its winding the upper front contacts of relay 204 to ground at the outer right back contact of relay 244. Since the relay 204, is in this 95 case, directly under the control of relay 202, ringing current is applied to the called line each time that the toll operator depresses her ringing key 121. The release of the established connection following the 100 termination of talking proceeds in the manner hereinbefore described and in accordance with the usual practice followed in establishing connections to private branch exchange.

Had the toll connection come from a toll point over the toll line 174 and over the toll district selector 175, then the connection would have been extended to the incoming selector of Fig. 2, directly over conductors 115 230 and 231 from the terminal bank of the 120 district selector 175. Following the seizure of the trunk conductors 235, 236 by the district selector 175, the distant toll operator then causes the setting of the incoming selector of Fig. 2 and the final selector of 125 Fig. 3 to connect with the wanted line. Following the complete extension of the toll connection to the terminals of the wanted line, the distant toll operator proceeds to 130 ring the wanted subscriber by depressing

- ner ringing key and causing the operation of ringing relay 172 at the district selector 175. The manner in which relay 172 is controlled is fully set forth in the aforementioned application of W. C. Jordan, Serial No. 680,807, filed Dec. 15, 1923, and since it forms no material part of the invention is not fully disclosed herein. Relay 172, upon energizing, applies current from the source 173 over the trunk line 235,236, causing the operation of relay 202. Ringing from the incoming selector through the operation of relay 204 then proceeds in the manner hereinbefore set forth.
- 15 The invention claimed is:
1. In a telephone system, an incoming line, an outgoing line, a source of ringing current, a relay for applying said source to said outgoing line, means controlled over the incoming line for operating said relay, means controlled over said outgoing line for discontinuing the operation of said relay to disconnect said source of ringing current, and means operative thereafter for rendering said relay responsive to said first means to apply and disconnect said source from said outgoing line at will.
  2. In a telephone system, an incoming line, an outgoing line, a source of ringing current, a relay for applying said source to said outgoing line, a second relay controlled over the incoming line, for operating said first relay, means controlled over said outgoing line for discontinuing the operation of said first relay to disconnect said source of ringing current, and means operative thereafter for rendering said first relay responsive to said second relay to apply and disconnect said source from said outgoing line at will.
  3. In a telephone system, an incoming line, an outgoing line, a source of ringing current, a relay for applying said source to said outgoing line, a second source of ringing current, means for applying said second source to said incoming line, a relay in bridge of said incoming line responsive to said second source for operating said first relay, means controlled over said outgoing line for discontinuing the operation of said first relay to disconnect said source of ringing current, and means operative thereafter for rendering said first relay responsive to said second relay to apply and disconnect said source from said outgoing line at will.
  4. In a telephone system, an incoming line, an outgoing line, a source of ringing current,
- a relay for applying said source to said outgoing line, a second source of ringing current, manually controlled means for applying said second source to said incoming line, a relay in bridge of said incoming line responsive to said second source for operating said first relay, means controlled over said outgoing line for discontinuing the operation of said first relay to disconnect said source of ringing current, and means operative thereafter for rendering said first relay responsive to said second relay to apply and disconnect said source from said outgoing line in response to each operation of said manually controlled means.
5. In a telephone system, an incoming line, an outgoing line, a source of ringing current, a relay for applying said source to said outgoing line, a second source of ringing current, manually controlled means for applying said second source to said incoming line, a relay in bridge of said incoming line responsive to said second source for operating said first relay, means controlled over said outgoing line for discontinuing the operation of said first relay to disconnect said source of ringing current, a supervisory relay operable over said outgoing line, and means under the control of said supervisory relay for rendering said first relay responsive to said second relay to apply and disconnect said first source from said outgoing line in response to each operation of said manually controlled means.
6. In a telephone system, a toll operator's position, a private branch exchange operator's position, selector switches for extending a connection between said operators' positions, a source of ringing current at one of said switches, a relay for applying said source over the established connection to said second operator's position, means controlled from the first operator's position for operating said relay, means operative following the response of the second operator for discontinuing the operation of said relay to disconnect said source of ringing current, and means operative from said second operator's position for thereafter rendering said relay responsive to said first means to apply and disconnect said source at will for recalling said second operator.

In witness whereof, I hereunto subscribe my name this 25th day of October A. D., 1923.

WILLIAM C. WEAVER.
